UNITED STATES PATENT OFFICE.

CHARLES B. HUDSON, OF AKRON, OHIO, ASSIGNOR TO THE AKRON STANDARD MOLD COMPANY, OF AKRON, OHIO, A CORPORATION OF OHIO.

VULCANIZER FOR INNER TUBES.

Application filed December 23, 1927. Serial No. 242,069.

The present invention relates to an apparatus for the vulcanization of inner tubes by the full-molded process, and particularly to the adaptation of the watch-case type vulcanizer for this purpose.

The objects of the present invention are to provide a vulcanizer of this type in which the mold is divided at its inner periphery at some distance above the inner circumference of the tube mold, in which the entire periphery of the mold about the vulcanizing cavity shall be fully heated so as to cure the tube evenly about its entire cross section. It is also an object of the invention to provide a construction in which the inner periphery of the tube cavity is enclosed by a ring which is heated by steam from the main section of the vulcanizer. Other objects are to provide means by which the inner ring may be accurately adjusted to reduce the rind or overflow to a minimum, the adjustment taking up the wear and compensating for any variations or inequalities in the mold sections.

A further object is to provide a simple and easily operated device for clamping the valve stem, thereby facilitating the rapid placement of the green or unvulcanized tube in the vulcanizer, and removal of the vulcanized tube. The other advantages to be secured by the improved vulcanizer construction shown and described herein, will be apparent to those skilled in this art. The detailed construction of the vulcanizer is not essential to the practise of the invention, it being possible to incorporate the invention in different specific modifications within the scope of the claims.

In the drawings in which the preferred embodiment of the invention is shown,

Figure 1 is a side elevation of a complete vulcanizer of the usual or standard watch-case type, adapted for the curing of inner tubes, a portion of the vulcanizer being broken away for the purpose of illustrating the internal construction;

Figure 2 is an enlarged section on the line 2—2 of Figure 1;

Figure 3 is an enlarged detailed section on the line 3—3 of Figure 1;

Figure 4 is a section view taken at the valve stem of the tube, a straight valve stem being shown in full lines, and a bent valve stem in dotted lines, illustrating the adaptability of the device for both forms of stem;

Figure 5 is a section on the line 5—5 of Figure 4;

Figure 6 is a view showing the underside of the vulcanizer in the valve stem region;

Figure 7 is an enlarged view of the parts shown in Figure 5;

Figure 8 is a section on the line 8—8 of Figure 7; and

Figures 9 and 10 are detail views of the nipple for conducting steam to the inner ring of the vulcanizer.

Many of the parts shown in the general views of the device are standard construction of watch-case vulcanizers, and details thereof will not be gone into except in so far as they are necessary to an understanding of the invention. It will also be noted, that many features of the present invention are applicable to other types and forms of vulcanizers than the watch-case type shown herein, and are not necessarily limited to application on that form of vulcanizer alone.

The watch-case vulcanizer herein shown comprises a central or stationary chambered section 1 which is mounted upon a support 2. The inner chamber 3 is for the circulation of steam being enclosed by removable and replaceable mold plates 5 which form the outer walls of the chamber, and are provided with surfaces 7 which form a portion of the cavity for the vulcanization of the inner tube 8.

As shown in the various views, the section 1 comprises less than half of the complete tube molding cavity, the lower or inner portion or periphery of the cavity being comprised in a separate ring 10 which extends beyond the inner circumference of the tube and for a portion of the opposite side thereof. The plate 5 and the inner ring 10 constitute approximately two-thirds of the complete molding cavity, the remainder being formed by a separable plate 12 which is removably and replaceably attached to the movable or swinging member 14. The movable member 14 is also chambered for the circulation of steam.

In vulcanizers of this type, in which a larger portion of the mold cavity is enclosed by one side or member of the mold, the larger mold section has either been cast in one piece, chambered throughout, or the portion of the mold constituting the inner ring has had no provision for the circulation of the steam therein. The latter expedient makes a cold

spot or area about the inner circumference of the tube mold, which is objectionable. The former expedient gives rise to difficult casting operations, it being very difficult to 5 properly cast a chambered mold member of the shape and size desired.

In the present invention the inner part is formed as a separate ring as has been described, which is hollow or chambered 10 throughout. The section 5 is recessed as at 16, about its entire periphery and the ring is seated within the recess, a tight, cylindrical machine fit being provided at the division line between the section 5 and the ring 15 10 as shown at 17. This division line is parallel to the axis of the mold so that the ring may be adjusted while maintaining a tight fit about the entire periphery of the mold. The ring is secured to the stationary 20 section 5 by means of bolts 18 which pass through lugs 19 formed in the ring 10 and are screwed into the section 5. In order to secure accuracy of adjustment and fit about the line 17, there are provided a plurality of 25 set screws 20 passing through secondary lugs 21 on the ring 10 and bearing against the section 5. By adjustment of the bolts and set screws an accurate adjustment of the ring may be obtained. The outer edge of the ring 30 10 is beveled as shown at 24 to fit tightly against a corresponding surface on the plate 12.

By means of the mounting of the inner ring 10 an adjustment of thousandths of an 35 inch may be made in the position of the ring 10. In this manner irregularities or slight variations which are apt to occur in the casting or machinery of the mold members may be compensated, a result not possible with 40 previous constructions. This construction also permits the mold to be adjusted to compensate for the wear between the parts, and the maintenance of tight joints at the various lines of parting about the mold cavity, particularly at the point 24 and at the parting 45 25 between the two mold sections at the outer periphery of the tube, so that excessive overflow or rind is obviated. As the ring 10 is advanced the slight projection or ridge obtained at the point 17 may be rectified by 50 filing or abrading over the joint. If desired, shims may be placed between the contacting surfaces of the ring 10 and the part 5.

Steam is admitted to and circulated 55 through the inner ring 10 from the chamber 3 at the points 30. Details at this point are shown in Figures 3, 9 and 10. A hollow nipple 32, having a head 33 thereon, is threaded into the stationary member 5, a packing 35 60 being compressed by the head in contact with the face of the member 5. In order to operate the nipple, its outer end is formed with a squared socket 36 which may be engaged by a wrench or tool through an opening 37 in 65 the opposite side of the ring, the opening be-

ing closed by a plug 38 when the parts are in position. The nipple may be tightened to make a fluid tight connection at any position of adjustment of the ring 10.

When the mold sections are closed, they 70 are tightly clamped together by any suitable means, here illustrated as a rotating locking ring 39 about the exterior of the mold unit.

The invention shown herein, also includes a clamping device for holding and clamping the valve stem in position, so that as the tube is placed in the mold, the valve stem may readily be snapped into place and held in place during the closing of the mold and the curing operation. Heretofore, the valve 75 stem has been inserted through a radial opening in the tube mold and then clamped by a set screw or similar device. This takes time and may be neglected or overlooked by the mold operator. In the present device the valve stem is clamped in position as the tube is placed in the mold. This improvement is shown in Figures 5 to 8 inclusive.

At the point where the valve stem is located, the inner ring 10 is notched or cut away to provide a flared or wedge shaped recess 40 which extends to the center line of the ring. A block 41 is secured in an arched recess 43 on the underside of the ring 10, this block being provided with a projection 42 which seats in a corresponding recess in the base of the ring, at the inner end of the recess 40, being shaped to fit around one side of the valve stem and form a seat. The underside of the block is provided with a lateral passageway 44 which permits the passage of the bent valve stem. Two lugs or ears 45 depend from the block and to these lugs are attached leaf springs 46 which are reversely bent as shown in Figure 8 to provide curled extensions 47 which normally project into the path of the straight valve stem 50. A wedge shaped filler block 52 is secured to the movable mold member and fills the cavity 40 when the mold is closed. 110

The operation of the valve stem holder is quite simple. When the mold is opened the operator passes the valve stem between the spring 46 which gives sufficiently to admit it, and closes over the outside and securely 115 clamps the valve stem against the part 42 of the block. The removal of the finished tube is correspondingly facilitated.

It will be appreciated that various modifications and improvements may be made in 120 specific embodiments of the invention, it being the intention to cover such modifications as fall within the scope of the invention and the allowed claims.

What is claimed is:

1. A tube mold comprised of two sections movable relatively to one another, and a ring secured to one of said sections and forming the inner periphery of the tube cavity, said ring being mounted on the said section for 130

- adjustment in a direction parallel to the axis of the tube.
2. A tube mold having a tube cavity therein, said cavity being completed by three mold sections two of said sections constituting the outer portion of the periphery of the cavity, and the third the inner portion thereof, the third section being adjustable in the direction of the axis of the tube.
10. 3. A tube mold composed of two sections, and a ring forming the inner periphery thereof, said ring being seated in a recess about one of the sections and adjustable in a direction parallel to the axis of the tube.
15. 4. A tube mold composed of two sections, a ring forming the inner periphery thereof, said ring being seated in a recess about one of the sections and adjustable in a direction parallel to the axis of the tube, and having a 20 beveled surface adapted to fit against a correspondingly beveled surface on the other section.
25. 5. A tube mold composed of two sections, a ring shaped section forming the inner periphery thereof, the outer surface of said ring shaped section fitting against a cylindrical wall on one of said sections, and means to secure said ring shaped section within the wall and to adjust it in an axial direction 30 therein.
35. 6. A tube mold composed of two sections, a ring shaped section forming the inner periphery thereof, the outer surface of said ring shaped section fitting against a cylindrical wall on one of said sections, and means to secure said ring shaped section within the wall and to adjust it in an axial direction therein, said means comprising bolts to secure the ring in adjusted position and set screws 40 to move it axially.
45. 7. A tube mold composed of two sections, a ring shaped section forming the inner periphery thereof, the outer surface of said ring shaped section fitting against a cylindrical wall on one of said sections, means to secure said ring shaped section within the wall and to adjust it in an axial direction therein, all of 50 said sections being chambered for the circulation of steam, and an adjustable conduit between the ring and the section on which it is mounted.
55. 8. A tube mold composed of two sections, a ring shaped section forming the inner periphery thereof, the outer surface of said ring shaped section fitting against a cylindrical wall on one of said sections, means to secure said ring shaped section within the wall and to adjust it in an axial direction therein, and beveled contacting surfaces 60 between the ring and the opposite section.
9. A tube mold comprising a chambered mold section, a chambered ring supported thereon, means to adjust the ring upon the section, and a hollow threaded nipple connecting the interior of the ring and the section.
10. A tube mold comprising separable sections, a passageway for the tube valve stem formed in one of said sections, and a spring mounted on one of the sections and adapted to 70 clamp the valve stem in position in the passageway.
11. A tube mold having a section with a recess therein for the accommodation of one side of the valve stem, a spring attached at 75 one end to the section and terminating opposite the passageway so as to bear against the opposite side of the valve stem.
12. A tube mold having a section with a recess therein for the accommodation of one side of the valve stem, and spring members attached to the section and projecting outwardly therefrom, the springs having oppositely placed terminals adapted to yield to 80 permit the entrance of the valve stem.
13. A tube mold having a section with a recess therein for the accommodation of one side of the valve stem, and spring members attached to the section and projecting outwardly therefrom, the springs having oppositely placed curled terminals adapted to yield to 85 permit the entrance of the valve stem.
14. A tube mold having a section with a recess therein for the accommodation of one side of the valve stem, spring members attached to the section and projecting outwardly therefrom, the springs having oppositely placed terminals adapted to yield to permit the entrance of the valve stem, and a second mold section having a portion adapted to 90 close the recess.
15. A tube mold comprising a stationary section, a movable section, a ring secured to one of the sections and forming the inner periphery of the tube cavity, a recess being 95 formed in the ring, a projection on the opposite section filling the recess when the mold is closed except for a valve stem passageway, and a yielding spring device at the base of the recess adapted to clamp the valve stem in 100 position.
16. A tube mold comprising a stationary section, a movable section, a ring secured to one of the sections and forming the inner periphery of the tube cavity, a recess being 110 formed in the ring, a projection on the opposite section filling the recess when the mold is closed except for a valve stem passageway, and a yielding spring device at the base of the recess adapted to clamp the valve stem in 115 position independently of the other section.
